UNITED STATES PATENT OFFICE.

NATHAN KLAU, OF NEW YORK, N. Y.

DESIGN FOR OIL-CLOTH.

SPECIFICATION forming part of Design No. 37,283, dated November 15, 1904.

Application filed October 24, 1904. Serial No. 229,861. Term of patent 3½ years.

To all whom it may concern:

Be it known that I, NATHAN KLAU, a citizen of the United States, and a resident of the city of New York, borough of Manhattan, in the county and State of New York, have invented a new, original, and ornamental Design for Oil-Cloth, reference being had to the accompanying drawing, in which the figure is a plan of an oil-cloth, showing my design.

I claim as new and desire to secure by Letters Patent—

The ornamental design for oil-cloth, herein shown.

NATHAN KLAU.
